Filed Apr. 22, 1968, Ser. No. 11,571

Term of patent 14 years

U.S. Cl. D83—1

Int. Cl. D6—01; D24—05

FIG. 1 is a front view of a bedside bag hanger showing my new design;

FIG. 2 is a top plan view thereof;

FIG. 3 is a bottom plan view thereof;

FIG. 4 is a rear view thereof;

FIG. 5 is an end view thereof taken from the left of FIG. 1; and

FIG. 6 is a sectional view taken in a transverse plane indicated by line VI—VI of FIG. 4, the dotted lines showing a mounting member for the hanger.

The broken lines are shown for illustrative purposes only.

I claim:

The ornamental design for a bedside bag hanger, as shown and described.
